UNITED STATES PATENT OFFICE.

J. SIDNEY GOLDSMITH AND HIRAM H. SMITH, OF NEW YORK, N. Y.

COMBINED SHADE AND CONCENTRATOR FOR ARTIFICIAL LIGHT.

SPECIFICATION forming part of Letters Patent No. 251,711, dated January 3, 1882.

Application filed May 5, 1881. (No model.)

To all whom it may concern:

Be it known that we, J. SIDNEY GOLDSMITH and HIRAM H. SMITH, citizens of the United States, and residing at the city, county, and State of New York, have invented a new and useful Improvement in Combined Shade or Reflector and Concentrator for Artificial Lights, as joint inventors, of which the following, taken in connection with accompanying drawings, is a full, clear, and accurate description.

The object of our improvement is to form a combination of a shade or reflector and concentrator which will increase the power and brilliancy of artificial light and which can be applied to artificial lights of all kinds.

In the drawings, Figure 1 represents a vertical section of the shade. Fig. 2 is a plan view of the concentrator or holder. Fig. 3 shows the shade and concentrator combined. Fig. 4 shows an ordinary gas-burner and globe; Fig. 5, a gas-burner provided with my improvement.

It consists of two parts, a reflecting-shade, B, and a concentrator, A. These parts may be attached together or may be made separate and placed in proper position for use on the light. The reflecting-shade is made of tin or other proper metal or material, preferably with bright surface, and is placed circumferentially around the light.

The other part of our invention is the concentrator, which is made of glass in any suitable form and provided with an opening, so that it can fit over the burner of the light.

What we believe to be the best and most powerful form of concentrator to be used in connection with the shading or reflecting part of our invention is described and claimed in an application for Letters Patent of even date herewith, consisting, essentially, of a glass center with radiating arms; but other glass concentrators may be used. The above-named

concentrator is shown in Fig. 2. This glass concentrator A is placed below the light and at right angles to the shade or reflector B, which rests upon it. The rays of light by this means are reflected from the sides of the reflector and thrown down and concentrated on the glass concentrator placed below the light and at right angles to the shade or reflector, and a very brilliant, concentrated, and intense light is thus produced from an ordinary gas-burner, and the illuminating power of the light or burner is increased very greatly.

We have found by careful experiment that if our reflecting shade and concentrator is applied to any ordinary gas-burner and the gas turned on two-thirds of its full force, as much and as brilliant a light is produced as is produced without using our invention when a full head of gas is on. If applied to other than gas-lights the force, intensity, and brilliancy of the light is proportionately increased.

We are aware of a hollow glass globe filled with water and running parallel and horizontally with the light, but such we do not claim; but

What we claim, and desire to secure by Letters Patent, is—

In combination with a glass light-concentrator consisting of a center portion having a convex lower surface and a series of radial arms having convex lower surfaces, a reflecting-shade placed above said concentrator so as to surround the light, substantially as specified.

In testimony whereof we have hereunto set our hands this 30th day of April, 1881.

J. SIDNEY GOLDSMITH.
HIRAM H. SMITH.
